UNITED STATES PATENT OFFICE

1,997,940

AMUSEMENT DEVICE

Carl Edward Lundberg, Walden, N. Y.

Application July 5, 1934, Serial No. 733,921

10 Claims. (Cl. 272—43)

It is an object of this invention to produce a mechanism which will propel vehicles, carriages, cars or chariots, over a stationary platform or track, in an undulatory path whereby the occupants of said cars will be amused, entertained and thrilled as they pass speedily along the platform in the cars describing the undulatory path across the platform.

It is an object of this invention to provide a mechanism comprising a substructure of a stationary platform and a rotary central turntable including particular cooperating centering means located on said platform and turntable.

It is an object of this invention to provide a particular guide means having swiveled connection with the rotary turntable for the individual bars which propel and control the movement of the cars.

It is an object of this invention to provide a particular connection between the bars and cars including particularly related cooperating buffers.

It is also an object of this invention to provide a substructure comprising a stationary gear having a removable section whereby the cranks carried by the smaller gears may be readily adjusted to a suitable sequence which may be variable and selective.

It is also an object of this invention to provide suitable and specially supported bearing construction for the small gears or pinions including their cranks as well as the centering means carried by the turntable.

It is a further object of this invention to provide a mutilated stationary gear whereby the path of travel of the cars may be modified as well as produce the sensation of something accidentally or erroneously released and running wild for a short interval of time which may be measured in seconds and/or fractions thereof.

It is a still further object of this invention to produce a balanced driving means for the rotary turntable.

Fig. 1 is a schematic plan of the major portion of my invention.

Fig. 2 is a longitudinal section of the free end of the hollow bar with springs or buffers and attaching means secured thereto.

Fig. 3 is a vertical section through the center of the invention showing the rotary turntable, stationary platform, and the gearing mechanism.

Fig. 4 is an elevation of the swiveled guide for one of the tubular bars.

Fig. 5 is an elevation of the swiveled guide showing the detachable side of the guide in initial

position of assembling represented by dotted lines.

Fig. 6 is a modification in elevation of the stationary gear showing a mutilated gear, and

Fig. 7 is a modified drive gear providing for the application of balanced forces to the gear carried by the rotary turntable.

The stationary gear 1 is secured to the stationary platform 6 by bolts passing through the ears 1b. The gear 1 has a main section and a detachable section 1a to permit adjustment of the pinions 3 and cranks 4. The drive gear 9 is secured to the turntable 2 by bolts passing through the ears 9b and at least a portion of the turntable.

The pinions 3 are provided with cranks 4 and bearings of bronze 17 located in the turntable 2 and the brackets 17a respectively for supporting the spindles 4a of the pinions 3. The inner lower portion of gear 1 is provided with a smooth inner surface to form a guide and centering means for the rotary turntable 2. The guide and centering

rollers 3r may be integral with the pinions 3 or they may be made as separate elements. The pinions 3 and the rollers 3r are mounted in superposed relation respectively on their spindles 4a. The swiveled guides 8 are mounted on the edge portion of the turntable 2 and they support and guide the bars 7 which extend through the guides 8. The bars 7 are pivoted to the cranks 4

through the medium of wrist-pins 5. The free end of the bars 7 are provided with pivot bearings 7a and spring-bumpers 7b. The bearings 7c are supported in substantially U-shaped strap irons 7a secured in the free ends of the tubular bars 7 as indicated in Fig. 2, wherein both the springs 7b, the strap iron 7a and the inserted portions thereof are secured in position by a plurality of rivets or bolts 7e.

The chariots or cars 20 are provided with suitable castors which roll over the stationary platform 6. The cars are also provided with corner buffers secured to their front corners which are adapted to silently engage the spring buffers 7b on the bars 7. The corner buffers are made of any suitable resilient means or material. Said cars are pivotally connected by a pivot bolt passing thru an arm 21 and the bearing 7c. A pair of apertured ears on the arms 21 are adapted to receive the pivot bolt. The cars are made partly in imitation of a small automobile body including an imitation radiator, hood and cowl, and they each have a hand rail adjacent the cowl in convenient position for grasping by the occupants of the car. The seats of the cars are suitably cushioned as indicated.

The turntable 2 is supported on a plurality of

rollers 19, mounted in brackets 19a. The track-way for the rollers 19 is fixedly secured to vertical supports of the stationary platform while the stationary gear 1 is fixedly secured to said track-way.

The brackets 18 are secured to the outer circumferential surface of the drive gear 9 and form bearing supports for the lower ends of the shafts 4a.

10 The drive shaft 22 is mounted in bearings 24. The gear pinion 23 is in engagement with the gear 9. A pulley 25 is secured on the shaft 22 and is adapted to be operated by a belt driven by an electric motor (not shown) or other suitable source of power. The bearings 24 are supported preferably on concrete pillars or posts 26 anchored in the earth or bed of concrete. The stationary platform 6 is supported on posts or pillars suitably and firmly anchored.

20 One of the swiveled roller guides 8 for the bars 1 is shown on an enlarged scale in detail in Figs. 4 and 5. The guide 8 comprises a frame having one removable side 8a which is shown in Fig. 5. The rollers or pulleys 8b are mounted on pins or spindles 8c. In order to bring the last spindle 8c into locking position it is necessary to have an attachable side as 8a carrying a pulley and an attachable locking means comprising a bolt or rivet 8e. Said side 8a having a slot 8f to receive a spindle 8c.

It will be observed that when the removable side 8a is properly secured in position all of the spindles or pins 8b will be effectively locked against endwise displacement. The lower side of each guide 8 is provided with a suitable swivel bolt 8d which is fixedly secured to the turntable 2.

It is observed that the ends of the spindles 8c, are beveled, but attention is called to the fact that spindles having stepped ends instead of beveled ends, may be effectively substituted for the spindles 8c shown in the drawing. It is merely essential that the spindles shall be mutually locked against endwise displacement.

45 The guides 8 are also provided with outwardly flared filler pieces slidably engaging the bearing washers 8i. Said pieces are secured to the guide 8 preferably by brazing or welding. These pieces are secured in position and bear movably 50 on the washers 8i and thereby prevent undue lateral tilting of the guides 8 when subjected to heavy pulls or pushes given to or received from the bars 7.

One of the filler pieces is provided with an 55 aperture 8h for insertion of the lower spindle 8c through the guide frame a roller 8b and removable side 8a. The other spindles 8c are inserted in suitable succession until they are all 60 in operative position except the last spindle 8c in the removable side 8a which is inserted and tilted into vertical position with said side thereby 65 mutually locking all of said spindles against endwise displacement when the removable or attachable side 8a is secured in position by the bolt or rivet 8c.

It is to be observed that each guide 8 is a safety 70 substantially foolproof, anti friction bearing and guide mechanism for the hollow sliding bars 7.

In the modification shown in Fig. 6 the stationary gear 1b is mutilated so as to propel the pinions slightly more than 180° so that the cranks shall have passed the dead center whereby the car or chariot so affected will give the sensation of running wild at least it will be free to find its 75 own position until the pinion engages another

section of gear teeth on the mutilated stationary gear. The gear 1b is provided with the same variety of centering and guiding surface as gear 1, but it does not have a removable section since there can be no fixed relation of adjustments of pinions 3 and gear 1b.

The double drive, shown schematically in Fig. 7, is a modification in which the driving force for the turntable is applied in a balanced manner so that the device may run more smoothly and more nearly free from vibration especially when the mechanism is being started. The double or balanced drive gear, shown in Fig. 7 may be readily substituted for the single drive gear

23. In fact the shaft 22b may be shaft 22 extended through bearing 24 and collar 27 at the right end of said shaft 22 and thereby produce a triple drive instead of a single or double drive. This variation is deemed to be obvious in view of the various drives already disclosed herein. In the double or balanced driving mechanism there are two shafts 22a, each carrying a pinion 23a engaging the gear 9. The adjacent ends of the shafts 22a are provided with bevel gears intermeshing with a driving bevel gear 25a which is propelled by the shaft 22b secured to said bevel gear 25a. The shafts 22a are supported in suitable bearings 24a. The shafts 22a and gears 23a and 25a carried by said shafts are maintained against longitudinal displacement by collars suitably located and secured on said shafts and engaging the innermost side surfaces of the bearings 24a. It is contemplated that shaft 22b will also be supported in position by suitable bearings (not shown).

It is assumed that minor changes may be made in the structural details of the mechanism disclosed without departing from the scope of the invention as contemplated and hereinafter claimed.

The undulatory path defined by the cars, as well as the sensation of the occupants thereof, will be modified in accordance with different speeds of operation. In the disclosure of Fig. 1 the pinions 3 and cranks 4 may be adjusted to produce a rhythmic and like motion simultaneously of all the cars, or they may be adjusted to produce a rhythmic and like motion in rapid succession or sequence, or they may be adjusted to move promiscuously, i. e. not in rhythmic simultaneousness or rhythmic sequence. This variety of adjustment capacity is very important because it is selective and thereby a new sensation can result to the occupants of the cars with every variation of adjustment.

When using the mutilated gear 1b, of course there can be no adjustment of the pinions 3 and cranks 4 because the pinions and cranks are free to rotate as propelled by the bars 7, when said pinions are out of engagement with the gear or toothed section of said gear 1b. In the use of this gear the sensation of accidental release and of running wild will vary greatly with the speed of the turntable.

It is also to be noted that arrows have been placed on various rotating parts to indicate the relative direction of rotation of said parts. The directions of rotation may be relatively reversed by the use of a drive belt applied crossed to produce one direction of relative rotation or a belt not crossed to produce the opposite variety of rotation. This selective quality of rotation is made possible by the fact that the features of the mechanism are symmetrical and therefore capable of operation successfully in either direction.

In view of the clear disclosure of applicant's invention, as set forth in the specification and drawings, the operation thereof appears to be clearly obvious. It is therefore deemed unnecessary to recite in further detail the specific operation of the invention.

What I claim is:

1. An amusement device including a stationary platform forming a support for vehicles and provided with a trackway and gear fixed thereto, a cutaway portion in said platform, a turntable located in said cutaway portion and having supporting rollers engaging said trackway, said turntable having a gear secured to the central portion thereof and depending therefrom, said turntable having bearings, receiving shafts, pinions secured on said shafts and meshing with the teeth of the stationary gear, said shafts having cranks on their upper ends, swiveled antifriction guides mounted on the edge of said turntable and extending upwardly therefrom, bars articulately connected to said cranks and extending through the guides, vehicles movably supported on said platform and articulately connected with said bars, cooperating centering means located on said shafts and said stationary platform gear, means to drive said turntable and thereby to propel said pinions, cranks, bars and vehicles whereby said vehicles are caused to travel in an undulatory path over said platform imparting to the occupants of said vehicles both amusing and thrilling sensations.
2. In an amusement device, the substructure, including a stationary platform supporting a vehicle, a rotary turntable centrally mounted in said platform, a swiveled antifriction guide mounted on the edge of said platform and extending upwardly therefrom, said guide having one pair of vertical rollers and one pair of horizontal rollers, a bar extending through said guide and engaging said rollers and articulately connected to said vehicle, cooperating resilient buffers symmetrically mounted on both said bar and vehicle, a crank carried on the edge of said turntable and articulately connected with said bar whereby rotation of said crank and turntable in either direction, will propel said vehicle over said platform in an undulatory path symmetrical to said platform.
3. In an amusement device, the substructure comprising a turntable, a swiveled guide mounted on the edge of said turntable, said guide comprising a frame having a vertical pair of rollers and a horizontal pair of rollers, said rollers being mounted on mutually locking spindles whereby each spindle is maintained against endwise displacement, said frame also having flared filler pieces engaging a wear plate or washer located on said turntable.
4. In an amusement device, the substructure including a stationary platform having a stationary gear fixedly secured thereto, a rotary turntable supported by said platform, said turntable having a depending gear engaging a train of driving mechanism, said turntable having roller centering means supported on shafts extending through said turntable, said stationary gear having a smooth cylindrical portion engaging said roller centering means, pinions fixedly mounted on said shafts and enmeshing with said stationary gear, said shafts having cranks located above said turntable and fixedly secured to said shafts.
5. In an amusement device, in accordance with claim 4, in which a plurality of gears of said train of gears, engage the depending gear, whereby balancing forces may be applied to said depending gear and turntable.
6. In an amusement device, according to claim 4, in which said train of gears is provided with three gears in engagement with said depending gear, whereby balancing forces may be applied to said depending gear and turntable.
7. In an amusement device, according to claim 3, in which the guide has one removable or attachable side swiveled on one of the spindles, said side carrying a roller and spindle and having a notch slot or recess adapted to receive another spindle as said side is tilted or swiveled to position and means to secure said side in assembled position.
8. In an amusement device, a stationary platform having a stationary gear secured thereto a rotary turntable having pinions enmeshing with the stationary gear said pinions having shafts provided with cranks, said stationary gear having a main gear section and a removable and attachable gear section whereby the pinions and cranks may be adjusted relatively to the stationary gear when said attachable gear section is removed, cooperating centering means on said turntable and said stationary gear.
9. In an amusement device a stationary platform having a stationary gear secured thereto, a rotary turntable supported by said platform, said stationary gear having toothed gear sections, pinions carried by said turntable, said pinions having shafts provided with cranks, said pinions adapted to engage the toothed sections, cooperating centering means on said turntable and said stationary gear.
10. In an amusement device, a stationary platform having a stationary gear secured thereto, a rotary turntable supported by said platform, cranks and shafts having pinions carried by said turntable cooperating centering means on said shafts and stationary gear, a gear secured to and depending from said turntable brackets secured to said depending gear and having bearings for the lower ends of said shafts, bearings in said turntable for the upper ends of said shafts, antifriction guide frames swivelly mounted on the edge of said turntable and extending upwardly therefrom, bars extending through the guide frames, one end of each bar being articulately connected to said cranks and the opposite ends connected to vehicles located on said platform, symmetrically arranged buffers on both the vehicles and the bars and means to drive said turntable pinions, cranks, bars and vehicles, whereby said vehicles are propelled about the platform in undulatory paths.

CARL EDWARD LUNDBERG.
